UNITED STATES PATENT OFFICE.

GEORGE A. JONES, OF LYNN, MASSACHUSETTS, ASSIGNOR TO SHOE PRODUCTS, INC.,
OF LYNN, MASSACHUSETTS, A CORPORATION OF MASSACHUSETTS.

SHOE.

Application filed December 24, 1926. Serial No. 156,928.

The invention to be hereinafter described relates to shoes, and more particularly to a simple, useful cushion which may be quickly and easily applied to various types 5 of shoes with slight alteration in the shoe construction, and is designed to promote the health and comfort of the foot of the wearer.

The character of the invention may be best understood by reference to the following description of embodiments thereof shown in the accompanying drawings, wherein:

Fig. 1 is a perspective view of a man's 15 shoe embodying the invention;

Fig. 2 is a plan of a filler and cushion;

Fig. 3 on an enlarged scale shows the construction of the under side of the cushion;

Fig. 4 is a longitudinal section taken on 20 line 4—4 of Fig. 3;

Fig. 5 is a transverse section taken on line 5—5 of Fig. 3;

Fig. 6 is a sectional view of a portion of 25 the heel of the shoe, and shows the punch for cutting out the slug from the insole;

Fig. 7 is a view similar to Fig. 6 showing the hole in the insole formed by punching out the slug;

Fig. 8 is a sectional view of the heel portion of the shoe showing the cushion in 30 position with its collar in the hole in the insole;

Fig. 9 is a section taken on line 9—9 of 35 Fig. 8;

Fig. 10 is a perspective view of a portion of a lady's shoe provided with a cushion embodying the invention;

Fig. 11 is a view of the construction of 40 the under side of the cushion shown in Fig. 10;

Fig. 12 is a longitudinal section taken on line 12—12 of Fig. 11;

Fig. 13 is a sectional view of the heel portion of the shoe and shows the punch for 45 cutting the slug from the insole; and

Fig. 14 is a sectional view of the heel portion of the shoe showing the rubber cushion applied thereto.

Referring to the drawings, in Fig. 1 is 50 shown a man's McKay shoe comprising the outsole 1, insole 3, upper 5 and heel 7 and equipped with a pulsatile resilient rubber heel cushion 9 embodying the invention.

One good form of rubber cushion em- 55 bodying the invention, comprises a prefer-

ably thin diaphragm 11 (Figs. 3, 4, and 5) having a collar 13 integral therewith and projecting from the under face thereof. The inner wall of the collar preferably meets the under side of the diaphragm with 60 a gradual curve. The upper face 15 of the diaphragm is substantially flat and the marginal portion 17 of the diaphragm projects out beyond the collar and tapers 65 gradually toward the periphery of the diaphragm. Within the collar is a cavity or pocket 19 serving a purpose to be described. Preferably the diaphragm and the collar are of oval form. Rubber cushions such as above described may be made in quantities 70 by suitably shaped molds.

The cushion may be applied to a shoe in the course of the manufacture thereof and conveniently in about the last step in the manufacturing process, or the cushion may 75 be applied to completed shoes by cobblers or by clerks in retail stores. To accomplish this, a punch, such, for example, as the punch 21 (Fig. 6) may be provided having a cutting edge of oval form and of a size and 80 shape substantially corresponding to the outer wall of the cushion collar. The punch is presented to the insole of the shoe above the heel and directly over the cavity 23 formed by the inturned margins 25 (Figs. 6, 85 7 and 8) of the counter, upper and lining projecting in between the insole and outsole of the shoe. Then by a blow or pressure on the punch, it is forced downward through the insole 3, thereby dieing out a slug 27. 90 The punch and slug are then removed leaving the hole 29 (Fig. 7) in the insole above the outsole. The rubber cushion is placed in the shoe with its collar 13 in the hole 29, and with the margin of the diaphragm resting upon the portion of the insole surrounding the hole, as will be noted in Figs. 1, 8 and 9. It is not necessary that the edge of the collar shall rest upon and have support from the outsole, since the cushion is adequately supported by the marginal portion 95 of the diaphragm which rests upon the insole.

Preferably the hole 29 in the insole has its forward end 31 (Fig. 1) formed sharper 105 than the corresponding end 33 of the collar, thereby leaving a space 35 which will allow the collar to expand therein and prevent the occurrence of a hard spot beneath the portion of the heel of the wearer which is directly 110

in front of the heel bone. This portion of the heel is very sensitive, and therefore it is desirable that the cushion shall be soft and yielding at this point with nothing beneath it to cause discomfort or injury to the heel of the wearer.

Referring now to Fig. 10, a heel portion of a lady's turned shoe is shown therein having an outsole 37 and a shank 39 between which are marginal portions 41 of the counter, upper and lining.

The cushion 43 (Figs. 11 and 12) for the lady's shoe is similar to the cushion described for the man's shoe, excepting that 15 the collar 45 is smaller and the diaphragm 47 projects further forward from the collar than in the cushion for the man's shoe, in order that it may be of gradually decreasing thickness from the collar forward and end 20 in a thin edge which will not cause discomfort or injury to the foot of the wearer.

To prepare the shoe to receive the cushion, a punch 49 (Fig. 13) is provided having a cutting edge corresponding substantially to 25 the outer wall of the collar 45. This punch is introduced into the shoe, over the shank at the heel of the shoe and over the cavity 51 formed by the inturned margins of the counter, upper and lining. By a blow or 30 pressure, a slug 53 is punched out from the shank, leaving a hole therein. Then the cushion 43 is presented to the shoe and the collar 45 inserted in the hole in the shank and the diaphragm placed upon the shank.

If the turned shoe is made with a filler 55 (Fig. 2) instead of a shank, the filler may have a hole 57 punched in the heel portion thereof and provided with a cushion such as the cushion 9 described, and here again the 40 hole will be above the cavity formed by the inturned margins of the counter, upper and lining which are interposed between the filler and outsole.

There are many important advantages in a 45 shoe equipped with the rubber cushion disclosed herein. The cushion may be easily and cheaply applied to Goodyear welt, McKay and turned shoes with slight change in the construction of the shoes. There is 50 no cutting through any seams or a plurality of parts. It is merely necessary to cut a hole in the insole, shank or filler. This does not detract from the strength of the shoe. The diaphragm is so thin that it does not 55 project up materially into the heel space of the shoe and therefore does not throw the foot out of the position it was intended to occupy in the design of the shoe.

The portion of the diaphragm over the 60 cavity within the collar is sufficiently thin to permit the same to flex up and down with pulsatile action when the wearer of the shoe is walking. When the foot is advanced and the heel of the shoe is brought to the ground, the weight of the wearer will cause the dia-

phragm to flex down in the cavity, and when the weight is transferred from the heel to the ball of the foot, the weight will be lifted from the diaphragm and allow the same to flex upward to its normal position. Pressure down on the diaphragm causes the outer wall of the rubber collar to press against the wall of the hole in the insole, and the inherent elasticity of the collar is such that the collar will assist in flexing the diaphragm 75 upward when the weight is lifted therefrom. The pulsatile action of the cushion tends to keep the same in elastic, efficient condition for its purposes.

The diaphragm may flex down into the cavity beneath it and assume a contour conforming to the shape of the base of the heel of the foot without localized abnormal pressure on the heel. Thus the cushion prevents painful growths on the heel bone, and this is especially valuable for children whose bones are soft and more susceptible to such injury. The diaphragm has sufficient area and thickness to protect the heel of the foot from injury and discomfort frequently 90 caused by ends of the nails in the heel of the shoe.

The curvature of the inner wall of the collar toward the bottom of the cavity provides a substantial shoulder at the juncture 95 of the collar with the diaphragm which prevents sharp bending of the diaphragm at the edge of the hole in the insole and prevents the heel of the wearer of the shoe from feeling said edge.

The oval or tapered collar of the cushion in the similarly shaped hole in the insole prevents lateral or longitudinal displacement of the cushion in the shoe and maintains the longitudinal axis of the diaphragm in 105 proper alignment with the length of the shoe.

When the heel of the foot sinks into the cushion, it tends to prevent forward slip of the foot in the shoe, and this is of special 110 importance in ladies' high heel shoes, since it prevents the foot from crowding forward into the toe of the shoe, and in pumps prevents the foot from pressing against the line of the edge of the upper. Thus the foot is 115 protected from swelling and irritation from this cause. The cushion tends to prevent side-slip of the heel in the shoe, and consequently tends to prevent lateral bulging or distortion of the counter and wearing 120 down of the tread face of the heel more at one side than the other. Also since the cushion holds the heel in proper place, it tends to prevent turning over of the ankle.

It will be understood that the term "sole" 125 in the claims is to be regarded as generic to an insole, shank, or filler.

Cushions similar to the cushions disclosed herein are also shown in my copending applications Serial No. 156,927, filed December 130

24, 1926, and Serial No. 164,465, filed January 29, 1927.

The invention is not limited to the specific embodiments shown, but various deviations 5 may be made therefrom without departing from the spirit and scope of the appended claims.

I claim:

1. In a shoe, the combination of an insole 10 having a hole in the heel portion thereof, and a rubber cushion comprising a thin diaphragm having a collar projecting from the lower face of the diaphragm into said hole and of a depth substantially the same as the 15 thickness of the sole, said diaphragm having a wide margin projecting out beyond the collar and resting upon the portion of the insole surrounding the hole, said diaphragm being adapted to pulsate over the hole when 20 the wearer of the shoe is walking.
2. In a shoe, the combination of a sole having a hole punched therein, and a rubber cushion having a collar in the hole for preventing displacement of the cushion and a 25 pulsatile diaphragm extending across the

collar and having a margin resting upon the portion of the sole surrounding the hole, said collar having a length somewhat less than the length of the hole to leave a space between the collar and the front of the hole 30 to allow for expansion of the collar and prevent a hard spot at the front of the collar and pressure from such spot on the heel of the wearer of the shoe.

3. In a shoe, the combination of an outsole, 35 an insole, counter and upper, the counter and upper having inturned margins between the insole and outsole bounding a space between the insole and outsole, said insole having a hole therein above said space, a rubber cushion having a collar fitting into said hole and projecting toward, but not into the outsole, and a pulsatile diaphragm 40 integral with the collar and having a margin projecting beyond the collar and upon the 45 portion of the insole surrounding the hole, said diaphragm being adapted to pulsate over the hole when the wearer of the shoe is walking.

GEORGE A. JONES.
